[57] **CLAIM**

The ornamental design for a tool storage bucket, as shown and described.

DESCRIPTION

FIG. 1 is a front elevational view of my new, original, and ornamental design for a tool storage bucket;

FIG. 2 is a right side elevational view thereof;

FIG. 3 is a top plan view thereof;

FIG. 4 is a rear elevational view thereof;

FIG. 5 is a left side elevational view thereof;

FIG. 6 is a bottom plan view thereof;

FIG. 7 is a top plan view of the present invention with the lid portion in an open position and the handle not shown for convenience and clarity;

FIG. 8 is a top plan view of the present invention with the lid portion in an open position, with the removable tray removed and with the handle not drawn for convenience and clarity; and,

FIG. 9 is an exploded perspective view of the present invention.
